US0D1026216S

(12) **United States Design Patent** (10) **Patent No.:** **US D1,026,216 S**
(45) **Date of Patent:** **** May 7, 2024**

(54) **MEDICAL INJECTOR**

(71) Applicant: **Sensile Medical AG**, Olten (CH)
(72) Inventors: **Joachim Axel Fett**, Berlin (DE); **Simon Bürdel**, Rombach (CH)
(**) Term: **15 Years**
(21) Appl. No.: **35/516,103**
(22) Filed: **Nov. 4, 2022**
(80) **Hague Agreement Data**

Int. Filing Date: **Nov. 4, 2022**

Int. Reg. No.: **DM/226084**

Int. Reg. Date: **Nov. 4, 2022**

Int. Reg. Pub. Date: **Jan. 27, 2023**

(30) **Foreign Application Priority Data**

CLAIM

The ornamental design for a medical injector, as shown and described.

DESCRIPTION

1. Medical injector
2. Medical injector
3. Medical injector
- 1.1 : Perspective
- 1.2 : Perspective
- 1.3 : Perspective
- 1.4 : Perspective
- 2.1 : Perspective
- 2.2 : Top
- 2.3 : Bottom
- 2.4 : Front
- 2.5 : Back
- 2.6 : Right
- 2.7 : Left
- 3.1 : Perspective
- 3.2 : Perspective
- 3.3 : Top
- 3.4 : Bottom
- 3.5 : Front
- 3.6 : Right
- 3.7 : Left
